UNITED STATES PATENT OFFICE

2,596,303

POCKET RAZOR BLADE KNIFE

Richard H. Stead, Revere, Mass.

Application April 23, 1949, Serial No. 89,278

4 Claims. (Cl. 30—151)

1

This invention relates to pocket razor blade knives.

In order that the principle of the invention may be readily understood, I have disclosed a single embodiment thereof in the accompanying drawing, wherein—

Fig. 1 is a side elevation of the casing of the pocket razor blade knife;

Fig. 2 is an outer end or edge elevation thereof;

Fig. 3 is an inner edge view of one of the two members of the casing;

Fig. 4 is a vertical longitudinal section of the entire device with the razor blade in concealed or protected position within the casing;

Fig. 5 is a vertical longitudinal section of said device with the razor blade in exposed, projected, or cutting position;

Fig. 6 is a horizontal or longitudinal, substantially central section;

Fig. 7 is a vertical, nearly central section showing the razor blade in concealed or protected position;

Fig. 8 is a sectional view similar to Fig. 7, but showing the razor blade held in exposed, projected or cutting position;

Fig. 9 is a side elevation of the razor blade;

Fig. 10 is an enlarged detail in horizontal, longitudinal section, broken away; and

Figs. 11, 12 and 13 are details broken away, of modified constructions for holding the members of the casing in closed position.

The object of my invention is to provide a razor blade knife that may be conveniently carried in a pocket, as, for example, in a man's lower vest pocket, which knife is inexpensive to manufacture, and wherein the razor blade may be quickly positioned firmly either in cutting position or in retracted position with the cutting blade entirely protected. Other objects of my invention will be evident from the ensuing description.

Referring more particularly to the figures of the drawing, the casing is preferably made of two like members 1, 2, preferably but not necessarily of equal size and made of any suitable material. Preferably I form the casing of plastic material, but it may be made of other material, such, for example, as stainless steel. The length of the two-part casing is, as best shown in Figs. 4 and 5, sufficiently greater than the length of the razor blade 3 to provide a sturdy construction, and it is of sufficient height or vertical extent to provide a sufficiently strong construction, and also to provide for two positions of the razor blade 3, namely, the concealed or non-cutting position thereof, shown in Figs. 4 and 7, or the cutting or exposed position thereof, shown in Figs. 5 and 8.

In order readily to indicate the top of the casing, I may and desirably do notch (as shown at 4) the upper ends of the meeting edges 5, 6 of the two members 1, 2. I may also, if desired,

2

provide through-openings 7, 8, as best shown in Fig. 1, to permit the casing to be hung upon a small hook or nail or attached to a key ring or the like.

The two members 1, 2, comprising the casing are held in their closed position, shown in Figs. 1, 4, 5 and 6, by means of any suitable formations, and desirably by a plurality of longitudinally extending pins, two being shown for this purpose at 9, 10 in Figs. 3, 6, 7 and 8. The employment of these internal pins, which are formed upon or secured to one of the members 1 or 2 of the casing at any desired points and project into openings in the other member into which they tightly fit, permits the outer surface of the two members 1, 2 to be smooth. However, any other suitable means or formation may be provided to ensure the two members 1, 2 to be held closely together, yet permitting them to be readily separated, so that the user may quickly shift the razor blade from one of its positions to the other.

While any suitable razor blade may be employed in the practice of my invention, the internal construction of the casing calls for a razor blade having a thickened rear or back edge, such as best represented at 11 in Fig. 9. The razor blade shown in said Fig. 9 is that known upon the market as the Gem razor blade having a thickness at the back edge of about $\frac{1}{2}$ " and at the cutting edge .009". It is usually provided with the central slot 12 and the end notches 13, 13.

As shown in Figs. 3, 6, 7, 8 and 10, each of the casing members 1, 2 is provided internally with a lengthwise extending slot 14 (in member 1) and 15 (in member 2). These slots are of sufficient combined length to receive and snugly hold the razor blade 3 when inserted therein. These two slots 14, 15 are in longitudinal alignment with each other when the parts are assembled, as shown in Figs. 6 and 10, and they extend to the very bottom edge of the casing members 1, 2, as indicated at 16 in Figs. 3, 7 and 8, so that the razor blade 3 extends out through said bottom edge, as indicated in Figs. 5 and 8, when said razor blade is in cutting or exposed position.

In order to provide for the two positions referred to, for the razor blade 3, I construct in each of the longitudinal slots 14, 15 a longitudinally extending, inwardly directed ridge 17, 18, as shown in Figs. 3, 7 and 8, which ridge construction provides the recesses 14, 15 at such area of merely sufficient size to receive the thin body portion of the razor blade 3, but not to receive the thicker rear or back edge 11 of the razor blade. Above and below the said ridge 17, 18, as best shown in Figs. 3, 7 and 8, there are the laterally wider recessed portions 19, 20, respectively above and below the ridge 17, 18, and of such sufficient width transversely of the casing to receive snugly or with a sufficiently tight fit, the relatively thick rear or back edge 11 of the razor blade 3, so that

it is held firmly in either position in which it may be placed. The longitudinal edges of the recesses 19, 20 are preferably beveled, as indicated at 21, 22 in Figs. 6 and 10, to permit the ready insertion of the razor blade 3. The term ridge is used generically to define each of two formations between which only the body portion but not the thickened rear or back edge of the razor blade can be received.

Assuming that the casing composed of the members 1, 2, is closed, with the razor blade 3 in the concealed position, shown in Figs. 4 and 7, the thickened rear or back edge 11 of the razor blade 3 is in the recess 19. If it is desired to use the device as a knife, the two members 1, 2 of the casing are drawn apart, exposing one-half of the razor blade 3, which is then grasped and withdrawn from the member 1 or 2, in which it is still positioned, and reinserted, but with the thick rear or back edge 11 of the razor blade 3 in the lower recess 20 and with the cutting edge of the razor blade 3 exposed, as shown in Figs. 5 and 8. Then the other member of the casing is slid into place, as shown in Fig. 5, and the knife is ready for use.

I have hereinbefore stated that any other suitable means or formations may be provided to ensure the holding of the two members 1, 2 closely together, yet permitting them to be readily separated.

In Figs. 11 and 12 I have shown other means than the pins 9, 10 for this purpose which may supplement such pins or be used in substitution therefor. In said figures, I have represented, in top plan view and in side elevation, a construction wherein a portion of the two meeting edges 5, 6 of the members 1, 2 are respectively provided at the top with a slight longitudinal prolongation which fits into a recessed or cut-away portion of the edge of the other member. In Fig. 11, the member 1 is, for this purpose, shown as provided with a projection 23 which fits into a recessed portion in the member 2, an edge of which recessed portion is indicated at 24. Desirably each prolongation is of the irregular construction shown.

In Fig. 12, which is a side elevation of a part of the member 2, the said member 2 is provided on the side illustrated, at the top, with the projection 25 fitting into a correspondingly shaped recess in the member 1. Below the said prolongations of the members 1, 2, the edges 5, 6 have the same construction and position as in Fig. 1.

In Fig. 13 is shown a second modified construction for the purpose of holding the two members 1, 2 tightly in closed position, yet permitting the ready separation thereof. In this figure, the upper or top edge of each of the members 1, 2 is narrowly longitudinally recessed to receive therein a metallic spring-like piece 26 which is riveted to the member 2 at 27, and is formed with two slight internal recesses 28, 29 to engage slight elevations 30, 31 formed upon the members 1, 2 respectively. At one end, as indicated at 32, the spring 26 is beveled or cut away so that a finger nail of the user may be inserted thereunder to spring it upwardly, so as to free it from the projection 30, and thus permit the ready separation of the two members 1, 2. The inner end of the groove for receiving the spring 26 is indicated at 33. It will be evident that the top edge of the members 1, 2 is substantially flush, inasmuch as the spring 26 is received in the groove referred to.

In the construction shown in Figs. 11, 12 and 75

13, the members 1, 2 are not notched, as indicated in Fig. 1.

Having thus described one illustrative embodiment of the invention, it is to be understood that although specific terms are employed, they are used in a generic and descriptive sense, and not for purposes of limitation, the scope of the invention being set forth in the following claims.

I claim:

1. A pocket razor-blade knife comprising a razor blade of a type having a cutting edge and a thicker backing edge and a two member casing wholly enclosing the blade when in concealed position therein, at both ends and also at both sides and at the back edge and the cutting edge thereof, the said casing comprising two, wholly separate members, each of a length and height to receive a substantial portion of the entire length of the razor blade, each of said two members of the casing being wholly closed at its outer end and comprising two parallel walls spaced sufficiently apart to provide a recess to receive flatwise therebetween one end portion of the razor blade, the said two recesses being 25 in longitudinal alignment when the said two casing members are brought into edge-to-edge relation with a razor blade therein, the said two recesses being of sufficient extent from top to bottom to receive the entire razor blade there- 30 in in concealed position, the said two recesses each having between the top and bottom thereof a longitudinally extending, inwardly directed ridge of sufficient size to receive between the walls of the ridges the thin body portion only 35 of the razor blade, the thick back edge of the razor blade being receivable in said recesses either above or below the said ridges, so as when in the upper position wholly to conceal the razor blade and in the lower position to expose for 40 use the cutting edge of the razor blade.

2. A pocket razor-blade knife in accordance with claim 1, wherein means are provided to hold the two members of the casing together, yet permitting them to be readily separated by pulling apart.

3. A pocket razor blade knife in accordance with claim 1, wherein, to hold the two members of the casing together, but permitting their ready separation, one of said members has fastened thereto a spring-like piece which extends lengthwise onto the other member, said other member having a holding formation to engage said springlike piece near its free end, so that such free end may be slightly flexed to disengage said spring-like piece from the holding formation.

4. A pocket razor blade in accordance with claim 1, wherein the top edge of one of said members has secured thereto a narrow metallic spring of sufficient length to extend at its free end onto and tightly fit against said other member when the two members are brought into alignment, so that a fingernail of the user may be inserted under the free end of the spring to facilitate the pulling part of the two members.
